Patent for Issue. May 9, 1873.

UNITED STATES PATENT OFFICE.

LUDWIG SUTRO, OF NEW YORK, N. Y.

DESIGN FOR A RUFFLE-STAND.

Specification forming part of Design No. 6,650, dated May 13, 1873; application filed April 19, 1873.

To all whom it may concern:

Be it known that I, LUDWIG SUTRO, of the city, county and State of New York, have invented a new and original Design for Stand for Exhibiting Ruffling Material, of which the following is a specification:

The nature of my design is fully represented in the accompanying photographic illustration, to which reference is made.

a in the design consists of a conical-shaped frame of any material, either circular, pyramidal, or polygonal, which is covered with the ruffling goods *b*, wound spirally thereon and forming a highly ornamental figure, as represented. *c* is the base and *d* is the top, consisting of a cap or flange.

These cones of goods are sold to retailers. The ruffling is by this means preserved in proper condition. The crimps are not crushed as they would be if the goods were packed in a box in the usual manner, and the goods can be shown and examined without disordering them.

I claim as my invention—

The design for a ruffle-stand, as herein represented.

LUDWIG SUTRO.
